INVENTOR.
Ernest W. Snow

BY

Frederick J. Church
his ATTORNEY

UNITED STATES PATENT OFFICE.

ERNEST W. SNOW, OF ROCHESTER, NEW YORK.

REFILLABLE FUSE.

Application filed July 28, 1920. Serial No. 399,527.

To all whom it may concern:

Be it known that I, ERNEST W. SNOW, a citizen of the United States, residing at Rochester, in the county of Monroe and 5 State of New York, have invented certain new and useful Improvements in Refillable Fuses; and I do hereby declare the following to be a full, clear, and exact description of the same, reference being had to the accompanying drawings, forming a part of 10 this specification, and to the reference numerals marked thereon.

My invention relates to electric fuses or more particularly to those of the refillable 15 cartridge type which comprise a tube of insulating or refractory material containing a fuse strip provided at its ends with metal members which are adapted to clamp the fuse strip within the insulating tube, 20 operate with clamping or contacting means to form an electrical connection for the passage of current, and be demountable to enable renewing of the fuse strip after burning. The object of this invention is to 25 provide an improved fuse which is economical of construction, easy to assemble, readily demountable for renewing and provided with simple means for affording good electrical contact with the fuse strip and 30 for clamping the same in position. To these and other ends the invention consists in certain improvements and combinations of parts, all as will be hereinafter more fully described, the novel features being 35 pointed out in the claims at the end of the specification.

In the drawings:

Figure 1 is a view of my assembled fuse.

Figure 2 is a view similar to Figure 1 40 with the end caps removed.

Figure 3 is a section on the line 3—3 of Figure 1.

Figure 4 is an end view of Figure 1.

Figure 5 is also an end view of Figure 45 1 with the adjacent end cap or nut and fuse strip removed.

Similar reference characters throughout the several views indicate the same parts.

In order to achieve a simplification in 50 construction and number of parts while at the same time possessing and fulfilling the usual requirements of refillable electric fuses of the cartridge type such as ready demountability and the maintenance of good electrical contact, the present invention has been perfected. In the drawings

the numeral 10 designates a tube of insulating or refractory material which is adapted to contain the usual fuse strip 11. As is common in the art, the fuse strip 11 may 60 be provided with a reduced portion 12 wherein rupture occurs and the tube 10 may or may not contain some suitable filler surrounding the fuse strip. Provided at each end of the tube 10 are end members 65 or ferrules 13 and 14 of metal or other suitable electric current conducting material, which are preferably provided with internal shoulders 15 for cooperation with the ends of the insulating tube 10. The ferrules 13 and 14 may be secured to the insulating tube by any suitable means, but for purposes of illustration, I have shown them secured by means of stamped out lugs 16 which firmly position the ferrules on 70 the ends of the tube. Each ferrule is provided with an outwardly projecting portion or cylindrical tongue 17 of reduced diameter cut away adjacent its base or which is longitudinally or axially grooved, slotted or 75 otherwise provided with a lateral opening at 18 for the reception of an end of the fuse strip 11. Each ferrule is provided with an end cap or nut 19 preferably of the same diameter as the main body portion of the ferrule, and provided interiorly thereof with screw threads 20 or other securing means cooperating with some form of securing means 21 on the cylindrical tongue 17 whereby the end cap 19 is adapted 80 to firmly position the bent over portion 23 of the fuse strip against the shoulder portion 22 of the ferrule adjacent or surrounding the outwardly projecting portion 17. In order to allow the nut 19 to be screwed 85 up against the shoulder 22, the base of the groove 18 and that portion 24 of the shoulder 22 which forms a seat for the fuse strip may be cut away or counter-sunk below the shoulder 22 by an amount less than the 100 thickness of the fuse strip in order that the end cap may still securely clamp the fuse strip in place and at the same time cooperate with the shoulder portion 22. The bent back end of the fuse strip 25 105 affords a convenient place for marking the size or capacity of the strip which may be readily seen when the fuse is assembled, as shown in Figure 1. Each nut 19 may be provided with an aperture or vent 26 110 in order to allow the escape of heated gases when the fuse strip blows from an over-

load of current. In order to provide for the use of a screw driver or other tool for disconnecting the end caps, a groove 27 is provided if desired.

5. Among the advantages of my improved fuse may be enumerated the simplicity and rigidity of construction. By having the fuse strip firmly clamped against the shoulder 22, a rigid abutment is provided therefor which is not liable to flex or bend. Having the end caps of the same diameter as the main body portion of the ferrule results in a neat appearance as well as a saving of metal. Each end connection for the 10 insulating tube 10 comprises a minimum number of parts, namely the fuse strip and two clamping members between which the fuse strip is secured. With the fuse strip seated in a groove 18 and bent 15 back as shown there is no likelihood of the end of the fuse closing the aperture 26. With the type of end caps shown facility of demountability is assured and it is 20 very easy to tell whether the fuse is blown or not. The adaptability of the end of the fuse strip 25 to be used for marking the size or capacity of the fuse enables fuse strips of different capacities to be used and 25 also insures a certain indication of the size 30 through the ready visibility of the back turned end 25. The protruding end of the fuse strip affords an easy means of determining whether one or more than one thickness or fuse strip is contained within the 35 cartridge or receptacle.

I claim as my invention:

1. In a fuse, the combination with an insulating tube of a metal end member secured to the tube having a threaded projecting portion having a lateral opening at the bottom thereof and a shouldered portion adjacent the projecting portion, a fuse with-

in the opening of the projecting portion and a clamping means in cooperation with the threads of the projecting portion to 45 clamp the fuse securely against the shoulder.

2. The combination with an insulating tube of a metallic end piece fixed to said tube and having a longitudinally grooved 50 externally threaded cylindrical tongue and a shoulder of larger diameter than said tongue, a portion of the shoulder being flush with the bottom of the groove in said tongue, and a nut in cooperation with the 55 tongue and shoulder which is adapted to retain a fuse clamped between the nut and shoulder.

3. In combination a refractory tube of insulating material, an end ferrule secured to the tube and having an externally threaded projecting portion of reduced diameter and a shoulder on the ferrule around the base of the projecting portion, an axial groove in said projecting portion extending 60 through said shoulder, a perforated cup shaped cap of the same diameter as the ferrule in engagement with said projecting portion and adapted to clamp a fuse strip 65 against said shoulder.

4. In a fuse the combination with an insulating tube of a conducting ferrule surrounding and secured to the tube and having a projecting portion having a lateral opening adjacent the base thereof to receive a fuse strip and a shoulder on the ferrule around the base of said projecting portion, the shoulder being slightly countersunk in alignment with the groove 70 in the projecting portion but to a depth of 80 less than the thickness of the fuse strip used and clamping means for holding the fuse strip in position against the shoulder.

ERNEST W. SNOW.
